HEAD-LAMP REPLACEMENT UNIT.

Application filed January 28, 1924. Serial No. 688,947.

This invention relates to an assembly for headlamps having particular utilization in connection with replacement reflectors for automobile headlamps.

Particularly in connection with an automobile headlamp, the practice has recently arisen of replacing a worn or inefficient reflector surface by a second or replacement reflector placed within and supported by the old reflector, thus giving the effect of a new reflecting surface. In applying the second reflector, various means have been employed such as edge flange attaching means which tend to distort the true parabolic curvature of the second reflector and give rise to various difficulties of adjustment.

Among the objects involved in the invention is, therefore, the inclusion of means whereby a secondary or replacement reflector is applied to the old or primary reflector of the headlamp construction by means of a single assembly unit. Another important object is the employment of an assembly unit which will permit the adjustment of the lamp either in the direction of the lamp axis or in a plane transverse thereto. It is an important object also, to provide means which will permit yield of the holding mechanism of the replacement reflector in accordance with variations in curvature of the primary reflector or supporting base. Still another object involved is the utilization of a yielding auxiliary support element for the replacement reflector which, by reversal, may be utilized for primary reflectors of different curvature. Various other objects are comprehended within the scope of the invention, including the provision of means for preventing direct glare through the shielding of direct rays emerging from the lamp filament, above a horizontal plane passing approximately through the center of or just below the lamp filament; the provision of a lamp shield which is removable from the lamp; the provision of a lamp shield which has a definite predetermined relationship with the lamp filament and with the nature of the curvature of the secondary reflector; the utilization of an opaque band, strip or shield toward the tip of the lamp tending to prevent passage of direct rays to that portion of the primary reflector which extends beyond the lower edge of the primary or replacement re-

flector; and various other objects involved in the details of the construction and methods of manufacture which will become apparent on consideration of the specific embodiment which may be preferred of the invention herein described and illustrated in the accompanying drawing.

Referring to the drawings of the application:

Fig. 1 shows a sectional elevation of a headlamp adapted to be used on a vehicle in which is inserted a secondary or replacement reflector and showing the various connecting elements entering into the complete assembly;

Fig. 2 is a view of a replacement reflector unit applicable to an ordinary primary reflector showing a fabric sheet covering in front of the reflector;

Fig. 3 is a detailed view of the auxiliary supporting element;

Fig. 4 is a view of a modified construction of the shield showing the application of the same to the bulb of an ordinary reflector; and

Fig. 5 shows a still further modification of the glare preventing shield.

Generally stated, the invention is comprehended in simplified means for connecting a replacement reflector to the ordinary reflector of the headlamp which includes means for rotatably and axially adjusting the lamp within the replacement reflector from a central tubular support insertible within the socket of the old reflector.

A feature of the invention is the provision of a shield adapted to be positioned in front of the lamp so as to cut off upwardly directed rays, a structure adapted to prevent glare in the lamp, particularly when utilized on a moving vehicle, and in such weather conditions where the presence of fog or mist makes it exceedingly difficult to operate a vehicle safely.

The invention, while having general applicability to lamps of various designs and uses, is herein shown as applied to an automobile headlamp 10 of a design including an outer casing 11, and a reflector 12 mounted within the same. As shown, the method of assembly involves the formation of a central aperture 13 in which is positioned a central cylindrical tube 14 adapted to hold a contact tube 15 within the same.

The reflector 12 has a central aperture 16 and an outer extending central flange 17 having the same diameter as that of the cylinder 14 and adapted to be inserted over the end of the contact cylinder 15, thus forming a unified tubular connection between the reflector and headlamp casing.

The outer edge of the reflector is expanded in a plane perpendicular to the axis thereof to form a narrow rim 20 having a central annular groove 21 in which is positioned a yielding cord fabric 22 adapted to contact with the lens 23 of the headlamp. The outer edge of the rim 20 is turned reversely and outwardly to form a contact surface 5 with the inside of the casing 11. Rim plate 24 is provided having an inner flange turned parallel to the reflector axis and contacting on its end with the lens of the headlamp and an outer flange 26 parallel to the flange 25 and overlapping and adapted to be removably attached to the outer rim of the headlight casing 11.

The contact tube 15 holds the electrical contacts, completing the circuit between the outside electrical source to which connection is made by the cord 29 and lamp bulb 30. The rear end of the tube 15 extends beyond the rear side of the casing 11 and is cut axially and radially on opposite sides in L-formation to form the slots 31 of a bayonet joint connection, the same being adapted to receive the pins 32, extending radially from the body of the plug 33 at the end of the connecting cord 29. The connecting plug 33 is formed of electrically insulating material with a central electrical contact plate 34.

Within the tubing 15 are positioned two plates 35 and 4, formed of dielectric material and held in position within the tube by means of annular inwardly directed depressions 36 and 3. In the body of the tube, blocks 37 and 2 are attached to the plates 35 and 4 adjacent their centers and through apertures passing through these plates and blocks, pins 38 and 39 are adapted to have axial movement. On adjacent ends of the pins 38 and 39 are formed integral therewith annular flanges 40 and intermediate these plates 40 a spring 41 is adapted to exert pressure, tending to hold the pins to the outer limits of their movement, the pin 38 against the contact plate 34 on the plug 33, and the pin 39 against the movable block 50, thus making connection with the base of the lamp 30.

The contact cylinder 15 is adapted to have axial movement within the tube 14 and the reflector tube 17, there being a slot 51 formed axially in the tube 14 through which lug 52, rigidly attached to the cylinder 15, extends. With this lug 52 an adjustment screw 53 is adapted to have screw-threaded engagement, the end of the screw 54 extending to the exterior of the casing where it may be manipu-

lated by the operator. A coiled string 55 surrounds the shank of the screw intermediate the casing and the outstanding lug 52, tending to maintain the cylinder 15 constantly at its innermost limit. It is obvious that by means of the screw 53 the operator may move the tube 15 axially within the casing to such a point of adjustment as secures the best results desired.

Fig. 2 shows the entire replacement unit adapted to be inserted bodily within the reflector of an ordinary headlamp when either by use or other cause, the original reflector has become relatively valueless as a reflecting medium. As illustrated in this figure, the unit includes a reflector 60, the outer edge of which terminates in a radially extending flange 61 to which is attached a sheet of paper or card-board 62. The purpose of the paper sheet or cardboard 62 is primarily to protect the finely finished reflecting surface of the reflectory unit during transportation from the point of manufacture to the distributor or user and also to prevent mal-adjustment of the movable portions of the unit by unauthorized persons. The purchaser of the unit may be assured if the paper sheet is unbroken that the lamp unit is in the condition in which it was originally assembled and responsibility for any defect in the construction may be readily ascertained. The center of the reflector is cut to form a central aperture 63, in which is adapted to be positioned the shoulder 64 of a holding members 65. The member 65 is positioned upon a tube 66 forming a plug 67 of diminished cross section and a socket 68 of increased cross section, the ends of the socket 68 extending within the reflector as separate yielding arms 69 having outturned ends 70. The holding member 65 rests upon these socket ends 69 adjacent to the outturned portions 70. The socket adjacent the junction of the plug 67 is externally screw-threaded and is adapted to receive a nut 170 in screw-threaded engagement therewith which is designed to be moved into close engagement with a washer 71, contacting with the central outer edge of the reflector 60 and bind the reflector to the holding member 65. It is apparent that rotation of the nut 170 in a direction to tighten the same upon the socket 66 will tend to force the holding member 65 inwardly against the inclined end 70 of the socket arms 69, this operation, as will appear from the description succeeding, binding the reflector closely to its means of support.

Similarly positioned on the screw-threaded socket is a second nut 72 which is adapted to bind against the first mentioned nut 170 through a washer 73. A central portion 74 of the washer 73 lies in a plane perpendicular to the axis of the socket 66 and an outer portion 75 lies in a surface inclined to the

plane of the central portion 74. The outer portion 75 of the washer 73 is split radially to form a plurality of sectors 76 and inasmuch as the material of which the washer 73 is formed is resilient, it is obvious that the washer forms resilient holding or supporting means when applied to the reflector in which the unit is to be positioned. This is apparent from consideration of the unit 5 as assembled in Fig. 1, the ends of the sectors 76 contacting against the surface of the original or primary reflector 12 of the head-lamp, yieldingly maintaining the tube 66 in proper relationship therewith. The plug 67 10 is provided with outstanding, oppositely positioned lugs 80 which are adapted to enter the bayonet slots 131 formed in the ends of the movable contact tube 15, this structure being the usual headlamp construction. 15 The socket 68 is adapted to receive the base of the lamp 30 and hold the same in proper contacting relationship with the replacement reflector 60. In addition to serving as a connecting means between the contact tube 20 15 and lamp 30, the plug 67 is adapted also to hold by means of a dielectric cylinder 81 a contact rod 82 movable axially therethrough. The cylindrical block 81 is held in position within the plug 67 by a down-turned flange 83 at the end of the plug and a plurality of inwardly directed indentations 84 formed in the plug adjacent the inner end of the block 81. The contact rod 25 82 is divided into two sections 85 and 86 which are held to each other by means of screw-thread 87. One end of the rod section 85 terminates in a contact plate 88 against which the pin 39 is adapted to have yielding connections and the other end of 30 the rod section 86 similarly is provided with a contact plate 89 adapted to contact with the base of the lamp 30. It is observable that the contact rod 82 is slidably positioned within the block 81 so that it may accommodate itself to the relative position of the lamp base and the end of the contact 39 and further that if the lamp base is abnormally fixed relative to the socket of the head-lamp by adjusting the two sections of the 35 connecting rod 82, a proper amount of separation may be obtained which gives the most efficient results for the particular head-lamp and reflector used.

In Figs. 1 and 2 there is illustrated a 40 novel form of connection intermediate the lamp bulb 30 and the replacement lamp socket 66 which is combined with means for preventing glare from the reflector. From a strip of metal a stamping is made which 45 at its central part is in the shape of a sector 90, this sector forming a shell conforming to the curvature of the lamp bulb 30 and covering a limited portion thereof, extending from a point somewhat below the axis 50 of the reflector including the filament of the lamp, to a point in front of a plane passing transversely through the filament of the lamp and above the axis thereof. The upper boundary of the sector is adapted to lie in a surface formed by passing a plurality of lines from the focal point 91 of the reflector, at which the filament of the lamp is positioned, to the outer edge of the replacement or secondary reflector 60, or, 55 as indicated in Fig. 1, in a plane transverse to the lamp axis and in front of the filament. In other words, the shield 90 is of such dimensions that rays of light emerging at the focus of the reflector 60 will be stopped by the shield 90 from passage to the front 60 of the reflector above a plane including the base 92 of the shield parallel to a plane passing to the axis of the reflector. Consequently, light rays will emerge only as reflected from the surface of the reflector 65 or such as pass out directly beneath the base 92 of the shield sector 90, these rays being inclined downwardly from the horizontal axial plane and thus not causing any glare to an observer in front of the headlamp. 70 Depending from the inner edge of the sector 90 and extending in a circular direction around the lamp bulb so as to join opposite sides of the sector is a band 93, the same 75 serving both as an auxiliary holding means for retaining the shield 90 in position and also as a shield for preventing the passage of direct rays of the lamp filament to that portion 94 of the original or primary reflector 12 which extends beyond the outer 80 edge of the secondary reflector plane 61. The shield 90, is held in position to the lamp bulb by means of lateral bands 94, 95, which 85 extend toward the base of the lamp and terminate in semi-cylindrical half tubes 96 and 97, the end of the tube adjacent the strap or band 94, having a greater diameter and curvature than the outer end 98. The two co-operating tube elements 96 and 97 are 90 adapted to fit over the base 100, of the lamp bulb and include between their edges the projecting pins 101 formed integral with the base of the lamp. The edges 99 of the tube members 96 and 97 adjacent the pins 101 are somewhat inwardly curved to form 95 surfaces adapted to contact with the pins 101 and thus retain the shield elements from axial movement on the lamp base. The portion of the tubes 96 and 97 adjacent the lamp bulb have a curvature less than the outer 100 portions 98 so that when the nut 170 is rotated in such a direction as to force the holding portion 65 upon the socket 66, the fingers 69 of the socket crowd the holding tubes 96 and 97 jamming the same into contact 105 with the lamp base and thus uniting the whole into one solid unit from which the possibility of vibration and rotation due to 110 jar or movement of the support is entirely 115 eliminated.

Attention is directed to several important features of the invention. In the use of replacement reflectors as heretofore employed, the attachment has been usually made at the flange at the outer edge of the replacement reflector and in such cases where the old reflector was off-center or distorted due to usage the replacement reflector also was moved off the axial center thereby so modifying the reflected light rays as to make the reflector highly inefficient and cause undesirable glare. In applicant's construction, the support and attachment is at the base of the replacement reflector and at the axis of the reflector, and the clamping of the attaching nuts tends to draw the whole unit into proper relationship with the axis of the replacement reflector and thus produce the most effective distribution of light and the least distortion of the reflected rays. It is pointed out further that there is a close relationship between the lamp bulb shield 90 the filament of the lamp bulb and the replacement reflector. The filaments generally used are of V-formation lying in a plane, the apex of the V being toward the front of the lamp. In order to give an undistorted reflection, the V plane is horizontal and the plane including the front edge 92 of the shield should also be horizontal in order to cut off the rays of light emerging from the V filament above a plane passing therethrough. Then also, especially in cases where a secondary reflector is used which is of the "flat-lite" type having vertical bar sections, it is essential for efficient illumination that the plane of the bars of the reflector be perpendicular to the plane of the filament so that in order to get the best results, the bulb shield, the filament, and the reflector should all have a certain predetermined relationship in their positions one to the other.

Attention is drawn also to the utility of the shield 90 in preventing glare under varied weather conditions especially in foggy weather where the light rays emerging from the lamp are subjected to multiple reflection from the various vapor particles, causing such diffusion of illumination as to make it exceedingly difficult for the operator of the car to visualize the objects in the path of movement of the vehicle. It has been found that by eliminating the rays of light which emerge in an upward direction from the headlamp that this secondary reflection of the light beam is very largely eliminated so that much clearer vision is obtained to the operator than would be obtainable without the employment of the shield 90. The aperture bounded by the shield 90 and the band 93, however, permits the emergence of those direct rays which illuminate the ground space directly in front of the car where illumination is essential.

A further feature of the invention is the employment of the axial support washer 73 with the flexible fingers 76 which have been found exceedingly useful in adjusting the replacement reflector to a distorted curvature of the primary reflector and to variation in sizes thereof. One method of attachment of the washer 73 is shown in Fig. 1, but it is obvious that by removing the nut 72 and reversing the washer so that the fingers spread forwardly instead of inwardly, that the unit could be readily adjusted either to another type of primary reflector having different dimensions or to a variation in the distances between the primary and secondary reflectors. This adjustment is facilitated by means of the adjustment screw 53 which shifts the whole contact connecting unit bodily inside the tube 15 and by tightening this screw the replacement reflector may be drawn rearwardly until the same is fit snugly in place against the primary reflector. Another aspect of the invention meriting attention is the combination of the shield by means of the straps 94 and 95 with the clamping shells 96 and 97, these shells being of a thickness approaching that of the pins 101. This construction permits rotation of the base of the lamp so as to place the filament in horizontal position and also in proper relationship with the replacement reflector where the reflector of the bar type is employed. This adjustment may be either in rotation or in axial movement, the construction permitting either adjustment, one as readily as the other.

Fig. 4 discloses a modification of the invention wherein a shield arrangement similar to that disclosed in Fig. 1 is utilized with a lamp bulb adapted to be inserted in the original reflector. This type of shield may be utilized either by the manufacturer of the lamp and supplied as part of the regular equipment, or the operator of the car may readily apply the same to the lamp bulb within the reflector. As illustrated, the clamps adapted to pass over the base of the lamp as shown in Figure 1 are eliminated, only enough of the metal being retained to form clamping arms 110 conforming to the curvature of the lamp and having outturned tips 111 adapted to facilitate placement on the lamp bulb. In the utilization of this form of the invention, the type of lamp bulb is used which when attached to the original reflector of the headlamp by means of the slot 112 and base pin 113 places the plane of the lamp filament 114 in a horizontal position and with the filament thus fixed, the shield 115 may be positioned on the lamp bulb so that its base lies in a plane parallel to the plane of the filament.

In Fig. 5 a still further modification of

- the shield is shown in which the sector 124 is mounted directly upon the lamp bulb as by paint or other nontransparent material. In the modification of Fig. 5, the base is illustrated as including a shell 120 split at its inner end as at 121 for a portion of the distances from the edge of the shell, the split portion terminating in a rounded aperture 122 adapted to fit over the pin 123 of the lamp bulb, this construction permitting insertion of the same in the socket of Fig. 1. Various other modifications of the invention will become apparent to those skilled in the art and therefore it is desired to protect fully all such modifications as come within the spirit of the invention and as defined by the claims hereto appended.
- Having thus described the invention, what is claimed is:
1. A replacement reflector unit positioned in a reflector of a lamp, comprising a reflector; a lamp bulb positioned in the reflector; a shield positioned in front of the lamp bulb; means for securing said reflector, bulb and shield together; and additional means for centering the replacement reflector within the primary lamp reflector comprising diverging resilient fingers attached to the base of the reflector and contacting at the free end of the fingers with the primary lamp reflector.
2. A replacement reflector unit comprising a reflector; a lamp bulb positioned in the reflector; a shield positioned in front of the reflector; means for binding said shield, bulb and reflector together, said means including a socket member having a flexible wall positioned in the reflector base; and a member mounted on the socket for binding the socket wall with the lamp bulb, shield, and reflector.
3. In a replacement reflector unit includ-
- ing a reflector; a lamp bulb and a bulb shield; means for holding said shield, bulb and reflector together, said means comprising an externally threaded shell socket having a flexible wall inserted in the base of the reflector and receiving the bases of the reflector and shield; and a nut in threaded engagement with the socket and movable in clamping relationship with said reflector and flexible socket wall.
4. In a replacement reflector unit for headlights, a reflector, a lamp bulb, a connector comprising a socket having a flexible wall receiving the base of the lamp bulb and positioned in the base of the reflector, and means for forcing the wall of the socket into holding relationship with the lamp bulb base and reflector.
5. In a replacement reflector for headlamps including a primary reflector, means for holding said replacement reflector in place within the primary reflector, said means including a tubular member secured to each reflector and a circular plate having flexible radial fingers fixed to the replacement reflector and adapted to contact with the primary reflector.
6. A replacement reflector unit comprising a reflector; an electric lamp bulb having a base positioned within the reflector; a shield positioned in front of the lamp and having supporting members connected with the base of said lamp and clamping means for holding said shield supporting members in engagement with the lamp base and supporting said reflector with respect thereto.
- In testimony whereof, we affix our signatures.

SAMUEL F. ARBUCKLE.
CARL P. BROCKWAY.
